UNITED STATES PATENT OFFICE.

CHARLES MEIER, OF HAVERHILL, IOWA.

PNEUMATIC ORGAN PLAYER.

1,405,932.

Specification of Letters Patent. Patented Feb. 7, 1922.

Application filed May 8, 1919. Serial No. 295,755.

To all whom it may concern:

Be it known that I, CHARLES MEIER, a citizen of the United States, and resident of Haverhill, in the county of Marshall and 5 State of Iowa, have invented a certain new and useful Pneumatic Organ Player, of which the following is a specification.

My invention relates to a certain new and useful improvement in the art of automatic 10 player attachments for organs, and my objects are to provide simple and inexpensive means that may be used on a reed organ, whereby the organ may be played by a slightly modified ordinary keyboard-player 15 having a perforated sheet, the perforations being adapted to admit air to work through pneumatic devices to valves.

A further object is to provide an attachment of this character, comprising a supplemental bellows, a valve box and an air operated motor, which may be combined with an ordinary organ and an ordinary organ player attachment, in such a manner that the supplemental bellows will coact with the 20 bellows of an ordinary organ to actuate the various devices of the player attachment; and further so constructed that when the organ is being played without the organ player the supplemental bellows playing 25 mechanism will not in any way materially increase the power required for furnishing pneumatic action to operate the reeds.

A further object is to provide means whereby the combined mechanism may be 30 operated from the ordinary organ pedal, thus dispensing with the necessity for the operator to pay any attention whatever to the means for supplying power to the music and take-up rolls when the device is being 35 used as an automatic player.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 is a vertical sectional view taken 40 on the line 1—1 of Figure 2, and having parts of the reed mechanism broken away to better illustrate the construction.

Figure 2 is a top or plan view of the device, parts being broken away to better illustrate the construction. 55

Figure 3 is a front elevation of my invention, with portions of the casing removed.

Figure 4 is a horizontal sectional view taken on the line 4—4 of Figure 1.

Figure 5 is a vertical sectional view taken 60 on the line 5—5 of Figure 1.

Figure 6 is a front elevation of the roll supporting cabinet or tracker box.

Figure 7 is a vertical, transverse, central 65 sectional view through the roll supporting cabinet.

Figure 8 shows an enlarged detail view of the reversing mechanism for controlling the movement of the player rolls; and

Figure 9 is a detail elevation showing a 70 portion broken away to show the tracker, said view also showing the relative position of certain of the air conducting tubes relative to the mechanism which they are designed to operate. 75

Referring to the accompanying drawings I have used the reference numeral 10 to indicate generally the ends of the casing in which my improved device is installed, between which are extended top and bottom 80 members 11 and 12.

Somewhat below the center of the casing is a transverse horizontal partition 13. Adjacent to the forward edge of the partition 13 the reeds of the organ, are supported, 85 one being shown in Fig. 1. Below this reed is an ordinary valve 13^a provided with an actuating stem 14 which is normally yieldingly held at the upper limit of its movement by means of a spring 14^b. 90

Below the partition 13 a bellows is disposed, which comprises a main rigid portion 15 and movable pumbers 16 at the front thereof. The movable portions 16 are hinged adjacent to their lower edges and 95 provided with valves 17 which may be constructed of a flap of paper designed to normally close an opening shown in dotted lines in Figure 3. Adjacent to the rear portion of the rigid portion 15 is a movable reservoir portion 18, which is normally held expanded by means of springs 19 which are secured to the frame by means of brackets 20. 100

A pedal 21 is pivoted to the front casing 22, adjacent to the lower portion of the casing, and has a laterally extending portion 23 which may be engaged by the foot of the operator for moving the pedal.

The inner end of the pedal 21 is pivoted at 24 to an upwardly extending link 25, which in turn is pivoted to the horizontal arm of a bell crank lever 26. The lever 26 is pivoted to a bracket 27 secured to the bottom of the partition 13, and the vertical arm of the lever extends to position adjacent to the movable bellows member 16, where it is pivoted to a bracket 28.

Extending upwardly from the pivot 24 and rotatably mounted thereon, is a link 29 which has its upper end pivoted to a substantially horizontal lever 30. The horizontal lever 30 projects through a transverse casing member 31 similar to the member 22, and is pivoted to said member intermediate of its ends. A clevis 32 is secured to the lever 30 outside the casing member 31 by a pin 33, and forms a bearing for vertical pintles 34. The pintles 34 are secured to an outwardly extending lever or handle 35 having a slot 36 therein in position somewhat spaced from the pintles 34. The outer end of the lever 30 is bent to extend through the slot 36 when the latter is in position substantially aligned with the lever 30.

From the description of the foregoing parts it will be seen that the handles or levers 35 may be swung on the pintles 34 to position where they are substantially aligned with the lever 30, at which time they may be moved up and down on the pivot of the lever 30 to thereby cause vertical reciprocation of the link 29. Reciprocation of the link 29 causes swinging of the pedal 21 by means of the pivot 24, and the parts are so arranged that the handle 35 or the pedal 21, or both, may be swung to cause reciprocation of the bellows member 16.

It will be noted that the pivot 24 is somewhat loosely received within the pedal 21, lever 38 and links 25 and 29, so that the difference in the pivotal lengths of the parts connected therewith will not cause the parts to bind.

Fixed to the bottom casing member 12, substantially midway between the front and rear edges thereof, is an upwardly extending bracket 37, to which is pivoted a lever 38. One end of the lever 38 is pivotally connected to the pivot 24, and the other end extends to position adjacent to the rear of the casing, where it is pivotally connected to an upwardly extending link 39.

Above the transverse partition 13 adjacent to the rear portion of the casing is a wind chest 40, having movable pumpers 41 pivoted thereto at 42 on a vertical axis. Valves 43 are provided for the movable pumpers 41, and are constructed to operate

in the same manner that the valve 17 operates.

Fixed to the bottom of the partition 13, adjacent to the rear edge thereof, are a pair of brackets 44, designed to pivotally receive bell crank levers 45. The horizontal arms of the bell crank levers 45 have their outer ends pivoted to the upper end of the links 39, and the vertical arms of the bell crank levers have their upper ends pivoted to brackets 46 extending from and secured to the pumpers 41.

From the construction of the parts just described it will be seen that swinging of the pedal 21, either by means applied to the pedal or to the handle 35, will cause swinging of the lever 38, reciprocation of the link 39, and by means of the bell crank lever 45 a horizontal reciprocation of the inner ends of the pumpers 41, thus operating them simultaneously with the main bellows.

A block 47 and a second block 48 mounted respectively above and below the partition 13 and between the wind chest 40 and the main bellows, have openings therethrough forming the passageway 49 indicated by the dotted lines in Figure 1, whereby free communication is permitted between the main bellows and the auxiliary bellows.

A valve casing 50 rests on the wind chest 40 and communicates therewith by means of a passageway indicated by the dotted lines in Figure 2. The chamber or casing 50 is divided into two compartments by a horizontal partition 51 having a pair of openings 52 and 53 therein, indicated by the dotted lines in Figure 4. These openings are provided with sliding valve members 54 and 55, which are operated to cover and uncover the openings 52 and 53 by means of valve controlling rods 56 and 57 extended through the walls of the casing.

Supported in the upper part of the organ casing by means of a casing 58 is a framework comprising three horizontally spaced members 60, 61 and 62, and vertical end members 63 and 64. This framework is designed to support the pneumatic playing means, and the horizontal members 61 and 62 are provided with central longitudinal openings 65 and 66 designed to communicate with an opening 67 through the casing 58. This opening or passageway is connected with the opening 49 through the block 48 to thereby connect these passageways in the members 61 and 62 with the bellows.

An ordinary organ reed (not shown) is placed in the path between the opening 67 and bellows 68, and when the bellows 68 are operated, it will cause the reed mechanism to operate.

Each playing device comprises a bellows 68 mounted on either the member 61 or 62 and communicating with the opening 67 through a passage 69. Communication 130

between the passageways 65 and 66 and the passageway 69 is normally prevented by a valve 70 normally held in closed position by a spring 71. The valve 70 is supported on 5 a stem or rod 72 which is mounted for horizontal transverse reciprocation within the members 61 and 62 as by means of an opening 73.

At the rear end of each rod 72 a bore 75 10 is formed within the members 62 and 63, within which extends a piston 76 secured to the rod 72. The rear ends of the cylinders 75 communicate with the tubes 77 which extend outwardly (see Figures 1, 7 and 9) 15 from the members 61 and 62 and which are adapted to form air-tight connections with flexible tubes 78.

From the construction of the parts just described it will be seen that a partial 20 vacuum will be caused by the operation of the bellows within the passageways 65 and 66, which will, however, not normally affect the bellows 68, as the valve 70 is normally held in closed position to prevent communication 25 between the passageways 65 and 66 and the bellows 68. If, however, air at atmospheric pressure be admitted through the tubes 78 to the cylinders 75 the pistons 76 will be moved by the pressure of the air 30 at atmospheric pressure to thereby move the valves 70 against the pressure of the springs 71 and permit communication between the 35 passages 65 and 66 and the bellows 68.

The movable leaves 79 of the bellows 68 40 extend forwardly and somewhat loosely receive rods 80. The rods 80 are screw-threaded adjacent to the members 79, and are provided with co-acting washers 81 and intermediate compressible pads 82, whereby 45 swinging motion of the members 79 caused by partially exhausting the air within the bellows 68 may cause vertical reciprocation of the rods 80.

The lower ends of the rods 80 are bent 50 to form a horizontal portion adapted to be pivotally received in the forward ends of levers 83. The levers 83 are pivoted substantially midway between their ends between brackets 84 extended down from the 55 members 62, and the forward ends of the levers 83 are normally yieldingly held at the upper limit of their motion by means of springs 85.

Vertical rods or wires 86 are somewhat 60 loosely received in the rear ends of the levers 83 and are provided with screw-threads adapted to coact with washers 87 and compressible pads 88 similar to the washers 81 and pads 82. The lower end of 65 each wire 86 is bent to form a horizontal portion which is pivotally received in the rear arm of the rock shaft 89. Each of the rock shafts 89 is pivotally mounted in a bearing 90 secured to a transverse frame member 91, and the forward end of the lever

is extended past the bearing 90 to position abutting against a washer or stop 92 secured to the valve stem 14 of the organ.

It will thus be noted that when air at atmospheric pressure is admitted to a tube 78 70 while the air within the bellows is at less than atmospheric pressure, then the parts just described will depress the valve stem 14 and play one reed in the organ.

Above the frame members 60 is mounted 75 a player roll casing comprising vertical frame members 93 and 94 and a horizontal top member 95. Substantially midway between the top 95 and the members 60 is a tracker 96 having a plurality of substantially parallel openings 97 extended therethrough. These openings 97 are in substantially horizontal alignment at the forward edge of the tracker 96, and diverge slightly from each other at the rear edge thereof, so 85 that laterally extending nipples 98 may be set into the tracker 96 around said openings. The free ends of the tubes 78 are pushed over the nipples 98 to form air-tight joints therewith. 90

Above the tracker 96 in the vertical walls 93 and 94 shafts 99 and 100 are journaled in alignment with each other and extended through the walls. The inner ends of the shafts 99 and 100 are provided with roll 95 engaging devices 101. The shaft 99 is mounted to allow horizontal reciprocation thereof, and is yieldingly held at the inner limit of its motion by means of a spring 102 and collar 103. The shaft 100 is secured 100 from longitudinal motion within the wall 94 by means of collars 104, and a pulley wheel 105 is secured to the outer end thereof.

Below the tracker 96 a shaft 106 is mounted in the wall 93 in a manner similar to the 105 mounting of the shaft 99. A shaft 107 is mounted in the wall 94 in alignment with the shaft 106, and held from sliding movement therein by washers 104.

From the construction of the parts just 110 described it will be seen that the music and take-up rolls have extended lugs 108 at either end thereof and be mounted within the receiving devices 101 by pushing the shafts 99 and 106 somewhat outwardly. 115

The player rolls heretofore mentioned comprise a strip of flexible material 109, such as paper, having a plurality of openings 110 therein.

It will thus be seen that movement 120 of the strip 109 past the member 96 will successively permit air to enter the openings 97, which will then pass through the tubes 78 and furnish air at atmospheric pressure to the cylinders 75, whereby the 125 reeds of the organ may be operated whenever an opening 110 registers with an opening 97.

Adjacent to the roll casing is mounted an air motor 111, adapted to be operated by the 130

4 partial vacuum within the bellows. A drive pulley 112 extends from the motor 111 and is connected by a belt 113 with a pulley 114 mounted on a horizontal shaft 115 which is journaled in brackets 116 and 117 supported by the frame members 60. The shaft 115 has a pulley 118 which is aligned with the pulley 105 and operatively connected therewith by means of a belt 119. The shaft 107 has a gear 120 mounted thereon, adapted to mesh with a gear 121 mounted on a stub shaft 122 which is rotatably and slidably mounted within the wall 94 in alignment with the shaft 115. Outside the wall 94 a clutch 123 having an annular groove therein is secured to the stub shaft 122. The clutch 123 has a pin 124 extended laterally therefrom, adapted to enter a notch in, or otherwise suitably coact with, the pulley 118 to lock the latter from rotation relative to the stub shaft 122. It will be noted that the stub shaft 122 is slidably but nonrotatably secured to the shaft 115, and that the pulley 118 is rotatably but nonslidably mounted on the shaft 115.

From the construction of the parts just described it will be seen that rotation of the motor pulley wheel 112 imparts rotation to the shaft 115. Rotation of the shaft 115 may in turn impart rotation to the shaft 100 by means of the pulley 118, belt 119 and pulley 105, to rotate the latter shaft in the same direction as the shaft 115 when the pin 124 is in engagement with the pulley 118. If, however, the collar 123 be moved to position to disengage the pin 124 from the pulley 118, it then moves the gear 121 into engagement with the gear 120 to thereby rotate the shaft 107 in a direction opposite to the direction of rotation of the shaft 115 and at a considerably slower speed.

Movement of the collar 123 therefore imparts rotation selectively to the player rolls in either direction.

45 The air motor 111 communicates through a tube 125 with the valve chamber 50, and is operated by the partial vacuum created within the bellows.

50 A bracket 126 is supported by the member 60 and the wall 93, and pivotally supports a bell crank lever 127 having a horizontal arm extended to position in front of the roll casing. The lower end of the vertical arm of the lever 127 is pivotally connected to a link 128, which in turn is pivotally connected to one arm 129 of a U-shaped lever having the horizontal portion 130 and an arm 131. The horizontal portion 130 is journaled in a bearing 132 secured to the member 60, and extends to position somewhat to the rear of the rear edge of the member 60.

Adjacent to the right hand end of the member 60 a support 133 pivotally supports

5 a lever 134, the rear end of which is pivotally connected to a link 135 extending between the arm 131 and the lever 134. The forward end of the lever 134 is pivotally connected to a link 136 which is slidably mounted in a bearing 137 near the middle 70 of the front edge of the member 60. The end of the link 136 is turned up to form a pointer or indicating device 136^a adapted to coact with marks or characters 138 on a plate 139 mounted on the top of the member 75 60 and within the roll casing.

80 A bracket 140 extends from the valve casing 50 and carries a lever 141 which is pivoted intermediate of its ends to said bracket. The forward end of the lever 141 is connected to the rear end of the lever 134 by a link 142, and the rear end of the lever 141 pivotally receives the end of the valve operating rod 56.

85 From the construction of the parts just described it will be seen that movement of the lever 127 operates through the links and levers described, to move the pointer 136^a in front of the plate 139 and to simultaneously move the valve 54 above the opening 52 to 90 regulate the amount of air drawn out of the upper chamber of the valve casing to the lower chamber. The lever 127 may also be moved sufficiently to close the opening 52 entirely, and it will be noted in this connection that while both valves 54 and 55 close the openings 52 and 53 the motor is entirely cut off from the bellows so that no power will be required for the motor when it is desired to play the organ by hand. 95

100 Supported by the wall 94 and the member 60 is a bracket 143 designed to pivotally support a bell crank lever 144 arranged similarly to the lever 127. The lower arm of the lever 144 is pivoted to a somewhat flexible rod 145. The left hand end of the rod 145, as shown in Figure 3, coacts with the annular groove in the collar 123 to move the collar longitudinally relative to the shaft 115. The right hand end of the rod 110 145 is extended to position past the right hand end of the member 60, where it is pivoted to the upper end of a lever 146 which is pivotally supported on an extension 147 from the frame member 64. 115

120 The lower end of the lever 146 is pivotally connected to a link 148 which is extended parallel with and along the front edge of the members 62 to position adjacent to the casing 58, where it is pivotally connected to a lever 149. The lever 149 is pivoted at its upper end adjacent to the upper portion of the casing 58, and its pivotal connection with the link 148 is substantially midway between its ends. The lower end of the lever 149 is pivoted to a link 150, which in turn is pivotally connected to a valve-operating lever 151. The lever 151 is opera-

tively connected with a valve 152 indicated by the dotted lines in Figure 3, which is adapted to close the passage 67 when in one position to thereby cut off the supply of air 5 from the bellows 68.

Somewhat below the extension 147 is a bracket member 153 which extends between the frame member 64 and the end casing member 10. Pivoted to the bracket 153, intermediate of its ends, is a lever 154 which is connected to the lever 146 by a link 155. The rear end of the lever 154 is pivoted to the end of the valve operating rod 57.

From the construction of the parts just described it will be seen that movement of the lever 144 to its upper position will throw the gear 121 into engagement with the gear 120 to thereby wind the music sheet for playing a piece. It also simultaneously 20 opens the valve 152 to thereby permit communication between the bellows and the reed operating bellows, and at the same time through the link 155 and lever 154 closes the valve 55, thereby forcing all the air received from the motor through the valve chamber through the opening 52.

When the lever 144 is moved to its lower position it moves the collar 123 to throw the pin 124 into engagement with the pulley 118 to thereby roll the rolls or music sheet in the opposite direction at an increased speed. Simultaneously it closes the valve 152 to prevent wasted power through the reed operating bellows, and opens the 35 valve 55 to thereby make the full power of the bellows available to the motor to thereby rewind the music sheet as rapidly as possible.

It will be noted that the levers 127 and 144 40 may be moved to position to entirely disconnect the player mechanism from the bellows so that the keys 156 may be operated in the ordinary manner to play the reeds by moving the valve stems 14 downward.

45 In the practical use and assuming that it is desired to transform an ordinary reed organ into a combined reed organ and automatic player device, using the same reeds, I provide within the organ casing the ordinary automatic player attachment, comprising rolls and a perforated sheet and air passageways leading from the perforations of the roll to the valve operating devices of the organ. This part of the device is of the 50 ordinary construction and of itself forms no part of my invention.

However, when the device is used as an 60 automatic player, then the operator can very easily and readily apply more power with his feet to the pedals and maintain through the main and supplemental bellows a sufficiently large amount of air currents to provide all that is necessary for both the reeds and for the air motor, because when

the operator is using his device, as an automatic player, his attention is not distracted by the necessity of operating the reed controlling device.

Some changes may be made in the construction and arrangement of the various 70 parts of the device without departing from the essential features and purposes of my invention, and it is my intention to cover by my claims any modified forms of structure or use of mechanical equivalents which may 75 be reasonably included within their scope.

I claim as my invention:

1. An automatic player attachment for reed organs of the class having vacuum creating means, said attachment comprising 80 bellows, means for operating the bellows simultaneously with the vacuum creating means of the reed organ, an air motor operated by the air flowing to the bellows, a valve arranged between the air motor and 85 the bellows for controlling the passage of air to the bellows, a perforated sheet feeding device, operated by the said air motor, and means controlled by the air passing through the perforations of the sheet for actuating 90 the organ keys.

2. An automatic player attachment for reed organs of the class having vacuum creating means, said attachment comprising 95 bellows, means for operating the bellows simultaneously with the vacuum creating means of the reed organ, an air motor operated by the air flowing to the bellows, a valve arranged between the air motor and the bellows for controlling the passage of 100 air to the bellows, a perforated sheet feeding device operated by the said air motor, and means controlled by the air passing through the perforations of the sheet for actuating the organ keys, and manually operated 105 means between said air motor and said perforated sheet feeding device for reversing the movement of the latter.

3. The combination with a reed organ having a bellows and pedals for operating 110 the bellows, and keys for controlling the air passages for the reeds, of an automatic player attachment comprising music and take-up rolls designed to receive a perforated sheet, an air motor operatively connected 115 with the music and take-up rolls, a second bellows operatively connected with the pedals for actuating the main bellows, and a valve between the air motor and the second bellows for controlling the passage of 120 air from the air motor.

4. The combination with a reed organ having a bellows and pedals for operating the bellows, and keys for controlling the air passages to the reeds, of an automatic 125 player attachment comprising music and take-up rolls designed to receive a perforated sheet, an air motor operatively con-

neected with the music and take-up rolls, a second bellows operatively connected with the pedals, a valve between the air motor and the second bellows for controlling the action of the air motor, means for providing communication between the main and the second bellows, and also between both of said bellows and the passageways lead-

ing to the organ reeds, a valve in said passageway from the bellows to the reeds, and means for controlling said valve automatically actuated upon a reverse of the rolls for rewinding.

Des Moines, Iowa, April 13, 1919.

CHARLES MEIER.
